(57) CLAIM

The ornamental design for a decontamination applicator, as shown and described.

DESCRIPTION

FIG. 1 is a front, left-side, bottom, perspective view of a decontamination applicator showing our new design;
FIG. 2 is a rear, right-side, bottom, perspective view thereof;
FIG. 3 is a front elevational view thereof;
FIG. 4 is a rear elevational view thereof;
FIG. 5 is a left-side elevational view thereof;
FIG. 6 is a right-side elevational view thereof;
FIG. 7 is a top plan view thereof;
FIG. 8 is a top plan view thereof with the optional ceiling box removed for clarity; and,
FIG. 9 is a bottom plan view thereof.

The broken lines immediately adjacent the shaded areas represent the bounds of the claimed design while all other broken lines are directed to unclaimed portions of the decontamination applicator and are for illustrative purposes only; the broken lines form no part of the claimed design.
